FIG. 1

FIG. 2.

BERYL B. COOPER
INVENTOR

BY James A. Giovane,
ATTORNEY

UNITED STATES PATENT OFFICE

95,120

DESIGN FOR A PORTABLE COFFEE GRINDER

Beryl B. Cooper, Portland, Oreg.

Application February 5, 1934, Serial No. 50,624

Term of patent 3½ years

To all whom it may concern:

Be it known that I, Beryl B. Cooper, a citizen of the United States, residing at Portland, in the county of Multnomah and State of Oregon, have invented a new, original, and ornamental Design for Portable Coffee Grinders, of which the following is a specification, reference being had to the accompanying drawing, forming part thereof.

In the drawing:

I claim:

The ornamental design for a portable coffee grinder, as shown.

BERYL B. COOPER.
